LIGHTNING ARRESTER

Filed Oct. 10, 1922

UNITED STATES PATENT OFFICE.

FRANKLIN S. SMITH, OF PHILADELPHIA, PENNSYLVANIA.

LIGHTNING ARRESTER.

Application filed October 10, 1922. Serial No. 593,511.

My invention relates to lightning arresters and it has for its general object to provide an improved and novel construction of lightning arrester which is particularly adapted 5 for the protection of high voltage systems.

It has for one of its objects to provide a novel construction of arrester which is adapted for use when immersed in a gas or gaseous mixture, under pressure,—say a 10 pressure on the order of ten atmospheres.

The desirable features of a lightning arrester are that it shall have a maximum discharge capacity; the lowest possible equivalent gap, which gap shall be what is known 15 as a "fast gap", and which also shall be constant, that is, for example, of a character not affected by the weather; the said gap shall also be of such character as not to cause noticeable surge on the line and should 20 discharge at a constant predetermined voltage. Hence, a further object of the invention is to provide a lightning arrester possessing all of these desirable characteristic 25 features and functions.

A still further object of the invention is to provide an arrester across which a discharge will be effected upon relatively small rise of voltage above the normal line voltage; and a still further object is to provide 30 an arrester characterized in that it is capable of controlling the dynamic or follow-up power current without interruption of the service.

Other objects and advantages of the invention will be pointed out in the detailed description thereof which follows or will be apparent from such description.

In order that the invention may be readily understood and its practical advantages 40 more fully appreciated reference may be had to the accompanying drawing in which an illustrative and preferred mechanical form or embodiment thereof is depicted; but it will be understood that changes in the details of construction may be made within the 45 scope of the claims without departing from the principle of the invention.

In the drawing:

Fig. 1 is a view showing portions of the 50 casing or tank of a transformer (in section) which is adapted to hold or contain a gaseous dielectric under pressure and connected with which is a high voltage terminal construction, the said terminal construction a 55 device embodying certain features of my invention, the said device being shown in sec-

tion and the said terminal construction being shown partly in section and partly in elevation;

Fig. 2 is a transverse sectional view taken 60 on the line 2—2 of Fig. 1; and

Fig. 3 is a top plan view of the metallic housing of the said device which housing constitutes one electrode of the arrester gaps.

Although the device is illustrated in the 65 drawings as being employed in connection with the high voltage line or system of a transformer it is to be understood that such application is merely illustrative and that it is not limited in its application to such specific use and that it may be applied to and employed with high voltage lines in connection with structures and devices other than transformers, an important feature being that the arrester shall occupy a position 70 within a volume of gas or a mixture of gases, such as nitrogen alone or a mixture such as air, or nitrogen and helium, under pressure preferably greater than atmospheric.

Referring to the drawing: 1 designates a 75 metallic bushing which projects through and is secured in an opening 2 through the casing or tank 3 of a transformer. Although the grounding is not shown in the drawings 80 it will be understood that the transformer casing is grounded.

4 designates a substantially tubular casing 85 of suitable solid dielectric, such as molded bakelite, which is secured upon a threaded outwardly projecting portion 5 of the bushing 1. The lead proper, which comprises the tubular section 6 and the lead wire 7, extends outwardly through the substantially tubular casing 4 and is secured within a 90 metal plug 26 which in turn is secured within the outer end of said casing. The tubular member 6 is thus held in rigid relation and, being associated with the lead wire 7 and with it in electrical connection with the metal plug 26 will thus be responsive to 95 the same potential as may be impressed upon the lead wire 7.

The intermediate electrode 8 of the arrester device is of tubular form and has 100 screw threaded connection with the base 9 of solid dielectric, such as molded bakelite. The opposite inner edges of the said electrode 8 are rounded off as indicated. The lead 6 extends through the electrode 8 and 105 is spaced from the inner surface thereof with which it is concentric. The construc-

tion of and employment of the tubular section 6, which, as will be seen from Figure 1, passes through the electrode 8, thus insures the maintenance of the intended and desired concentric relation between itself and the electrode 8. The gap is of the necessary configuration and dimensions to form a fast gap. Strips 10 of mica of non-uniform width are wound spirally and in 10 counterclockwise direction about the electrode 8 as indicated in Figs. 1 and 2, although, if desired, the winding may be in the opposite direction. This spiral is continued at the point indicated by the heavier 15 shading with fibre ribbon 11 which is of uniform width as indicated. The use of fibre ribbon instead of mica is merely for the purpose of economy.

The completed spiral which comprises 20 the mica strips 10 and the fibre ribbon 11 is surrounded or inclosed by a circular metal band clamping and compressing device 12 which is provided at its opposite ends with outwardly extending projections 12^a and 25 12^b, the latter (see Fig. 2) being longer than the former. These projections are provided with openings through which extends a bolt 13 by means of which the ends are adapted to be drawn toward each other to tightly 30 clamp the said spiral strips and ribbon. The metallic housing 14 which supports the base member 9 together with the intermediate electrode 8 and the spiral mica strips, fibre ribbon and clamp thereon, is supported 35 upon the lower inwardly projecting end of the bushing 1, having screw threaded connection therewith as indicated at 15. The intermediate portion of the housing 14 is tubular and somewhat enlarged with respect 40 to the screw threaded portion (which is connected to the lower screw threaded end of the bushing 1) and terminates in an outwardly extending flange portion 16 from which depend the feet 17 (see Figs. 2 and 45 3) which terminate in outwardly extending projections 18 having openings therethrough through which bolts 19 extend. These bolts 50 extend through openings in proximity to the outer edge of the flat disk shaped base 55 9 and the latter is held in position against the under sides of the said projections 18 by means of nuts 20 (Fig. 1) upon the lower ends of the said bolts 19.

The feet 17 are also provided with web-like portions 21, one at least of which is provided with a hole 22 through which one end of a bolt 23 (Fig. 2) extends; the said bolt also extends through the projection 12^b and upon tightening the said bolt by means 60 of the nut 24 the mica strips 10 and fibre ribbon 11 are still further tightened and held in the position as indicated and shown in Fig. 2 of the drawing.

It will be observed that the upper edges of 65 several of the outer spirals of the mica

strips and of the spiral ribbon 11 are in contact with the under side of the flange 16 (see Fig. 1) and also that the mica strips 10, the ribbon 11 and the clamping metal band 12 are housed within the space within 70 the feet 17, the base 9 and the upper portion of the housing 14.

The protective value of any lightning arrester gap or gaps is dependent not only upon the lightning or transient spark over 75 voltage but also upon the condition of the apparatus which is dependent upon various factors, an important one of which, in the case of exposed arresters, is the weather. The arrester embodying my invention and 80 as disclosed herein is employed within an air-tight casing or tank and therefore its operation is independent of weather conditions, in consequence of which it has a high 85 "protective ratio". In other words, it offers a high degree of protection.

If a solid dielectric, such as mica, is placed between electrodes, arcs due to impulse voltages (such as the voltages due to the transient energy of lightning charge) generally 90 follow the surface. If the dielectrics are smooth the impulse ratio is nearly unity even when the field is not uniform and the surface relatively long. When the dielectric surface has corrugations or is rough, the 95 impulse arc still generally follows the surface, but the impulse ratio is higher; that is, greater time is required for impulse surface spark over. As already indicated, my 100 arrester is adapted particularly for use when immersed in a gas or gaseous mixture under pressure greater than atmospheric and when so immersed the dielectric spark lag decreases with increasing gas pressure.

In operation, therefore, an arrester embodying my invention has low dielectric 105 spark lag because the corrugated solid dielectric is situated within a volume of gas or gaseous mixture which is under a pressure greater than atmospheric, say of the order of 110 ten atmospheres, and because of the fast gap.

In the operation of the device and in case the line including the said device should become charged with transient energy sufficient to effect spark over such spark over 115 occurs from the member 6 of the transformer lead through the gaseous filled gap to the intermediate electrode 8, thence by surface spark over from the intermediate electrode 8 along the surface formed by the 120 uneven upper edges of the mica strips 10 to the portion 25 of the housing 14 (which constitutes an electrode) and thence to ground; but the dynamic power current is unable to follow such impulse spark over. Furthermore, the discharge due to the transit energy or transient impulse is along radial paths and, in consequence, the impulse current density is maximum at the axis or center of 125 the device and minimum at the portion 130

of the housing 14; as the distance from the center of the device toward the portion 25 of the housing 14 increases the impulse current density decreases and, in consequence, the 5 dynamic or power current is less able to follow.

An arrester embodying my invention as herein disclosed and described has a high discharge rate, causes no noticeable surge on 10 the line, discharges at a constant predetermined voltage, is effective on high voltages, requires no charging current, is cheap, and is not liable to get out of order.

Having thus described my invention what 15 I claim and desire to secure by Letters Patent is:

1. In a protective device, in combination, a grounded member; a line conductor; and means interposed between said line conductor 20 and said grounded member, said means including a spark gap adapted to break down at a predetermined voltage and means formed of solid dielectric material for conveying current due to transient energy in 25 substantially radial paths and shaped to provide a surface, for the passage of said current, of an area increasing in the direction in which said current flows.

2. A protective device of the character 30 described comprising a conductor or line for conveying current, and a disk-like body consisting of strips of solid dielectric spirally arranged in a plane substantially at right angles to the line, the said disk-like body being adapted, when in the presence of gas 35 under pressure, to convey current along an exposed surface in approximately radial paths from the said line.

3. In a protective device, the combination 40 of the line for conveying current and a disk-like body consisting of strips of solid dielectric spirally arranged in concentric relation to and in a plane substantially at right angles to the said line and between the line and the 45 ground and being in series with a "fast gap" intermediate the line and the ground.

4. In a protective device adapted for use 50 in connection with a high voltage apparatus, the combination of a high voltage lead and a disk-like body consisting of strips of mica spirally and concentrically arranged with respect to the axis of said lead, a tank containing gas under pressure and one surface of the said disk-like body being in contact 55 with the gas in said tank and the said arrester including a "fast gap" which is in series with the lead, substantially as described.

5. In a protective device for the protection 60 of high voltage systems, the combination of a grounded tank containing gas under pressure, an intermediate electrode consisting of a tubular member concentrically arranged with respect to a portion of said line, the 65 inner surfaces of said tubular electrode being

spaced from the said line to form a "fast gap", a disk of solid dielectric provided with an opening concentric with a portion of said line in which the said electrode is secured, a plurality of strips spirally arranged around the said electrode, the said strips being of different widths and one edge of each strip being in contact with the adjacent surface of the said disk, the said edges thereby occupying positions in the same plane whereby an undulating opposite surface is provided, and a housing contacting with the upper edges of one or more complete coils adjacent the periphery of the body formed by the said spirally arranged strips, which housing has 80 connection with the said tank and is thereby grounded.

6. In a protective device for high voltage systems, the combination of a line, an electrode consisting of a short tubular member 85 through which a portion of said line extends, which tubular member is in concentric relation to the portion of said line which passes therethrough, a disk of dielectric material having an opening within which the said 90 electrode is secured, grounded metallic means for supporting the said disk and a plurality of strips of non-uniform width spirally wound around the said electrode with one edge thereof in contact with the adjacent side 95 of the said disk of solid dielectric, the said spirally wound strips constituting a disk-like body, the upper edges of one or more of the outer spirals being in contact with the said metallic supporting means, substantially as 100 described.

7. In a protective device for the protection of high voltage apparatus, the combination of a casing, a high voltage lead extending from the interior of said casing, a disk of 105 solid dielectric having an opening therethrough through which the said lead extends, metallic means having connection with the said casing and with the said disk for supporting the latter, the said metallic 110 means constituting an electrode, an intermediate electrode concentrically arranged with respect to the said lead and separated therefrom by a "fast gap" and a disk-like body of solid dielectric, one side of which is 115 seated against the said supporting disk and the opposite side of which is exposed, the surface of said opposite side being of undulating conformation and the outer portion of said disk-like body being in contact with 120 the said metallic means for supporting said first named disk.

8. In a protective device adapted for the protection of high voltage apparatus, the combination of a casing, a lead extending from the interior of said casing, a disk of solid dielectric having an opening therethrough through which the said lead extends, the said lead and opening being in concentric relation with respect to each other, a metallic 130

- housing supported within the said casing, means for connecting the said solid dielectric disk with said housing to support the said disk thereon, the said housing constituting an electrode, an intermediate tubular electrode secured within the opening through said disk in concentric relation with respect to the said lead and separated therefrom by a "fast gap", a plurality of strips of mica spirally wound around the said intermediate electrode to form a body of disk-like shape, one edge of each of said strips being in contact with the inner surface of the first named disk and the said strips being of different widths whereby the inner surface of the said disk-like body formed by the said strips comprises elevated and depressed spiral surface portions and the edges of one or more of the outer spirals being in contact with the said metallic means for supporting the said first named disk, substantially as described.

9. In a protective device, in combination, a grounded member, a line conductor, and means intermediate of said member and said line conductor for conveying current due to transient energy from said line conductor to said member, said means including a plurality of strips of solid dielectric material of different widths and arranged flatwise against each other.

10. In a protective device, in combination, a grounded member, a line conductor, means formed of solid dielectric material intermediate between said line conductor and said grounded member for conveying current due to transient energy in substantially radial paths from said line conductor to said grounded member and shaped to provide a surface for the passage of said current of an area increasing as the current approaches said grounded member, a gaseous dielectric under pressure, and means for confining said gaseous dielectric so that said last-mentioned means is subjected thereto.

11. In a protective device, in combination, means adapted to be grounded and including a ring-like conductive member, a line conductor passing through said ring-like member but spaced therefrom, and a disk-like member of solid dielectric material intermediate of said line conductor and said ring-like member and provided with an irregular surface for conveying current due to transient energy in substantially radial paths from said line conductor to said ring-like member.

12. In a protective device, in combination, means adapted to be grounded and including a ring-like conductive member, a line conductor passing through said ring-like member but spaced therefrom, an electrode about and spaced from said line conductor and adapted to form therewith a spark gap, and dielectric means interposed between said

electrode and said ring-like member for conveying current from said electrode to said ring-like member.

13. In a protective device, in combination, means adapted to be grounded and including a ring-like conductive member, a line conductor passing through said ring-like member but spaced therefrom, a disk-like member of solid dielectric material intermediate of said line conductor and said ring-like member and provided with an irregular surface for conveying current due to transient energy in substantially radial paths from said line conductor to said ring-like member, a gaseous dielectric under pressure, and means for confining said gaseous dielectric so that the effective surface of said disk-like member will be subjected thereto.

14. In a protective device, in combination, means adapted to be grounded and including a ring-like conductive member, a line conductor passing through said ring-like member but spaced therefrom, an electrode about and spaced from said line conductor and adapted to form therewith a spark gap, dielectric means interposed between said electrode and said ring-like member for conveying current from said electrode to said ring-like member, a gaseous dielectric under pressure, and means for confining the latter so that the gap between said line conductor and said electrode as well as the effective surface of said dielectric means will be subjected thereto.

15. In a protective device, in combination, a tank adapted to contain an electrical apparatus and having confined therein a gaseous dielectric under pressure, a line conductor passing through a wall of said tank and insulated therefrom, and means intermediate of said tank and said line conductor for conveying current due to transient energy from said line conductor to said tank, said means including a plurality of strips of solid dielectric material of different widths and arranged flatwise against each other and subjected to said gaseous dielectric.

16. In a protective device, in combination, a grounded member, a line conductor, means intermediate of said member and said line conductor for conveying current due to transient energy from said line conductor to said member, said means including a plurality of strips of solid dielectric material of different widths arranged flatwise against each other, a gaseous dielectric under pressure, and means for confining said gaseous dielectric so that said intermediate means is subjected thereto.

17. In a protective device, in combination, a tank adapted to contain an electrical apparatus and having confined therein a gaseous dielectric under pressure, a ring-like electrode within said tank, a line conductor passing through a wall of said tank and

- through said ring-like electrode, a housing of solid dielectric material for insulatingly supporting said line conductor and for holding said conductor in predetermined spaced relation to said ring-like electrode, thereby to form therewith a spark gap, and dielectric means interposed between said bushing and said tank for conveying current due to transient energy from said ring-like electrode to said tank.
18. In a protective device, in combination, a tank adapted to contain an electrical apparatus and having confined therein a gaseous dielectric under pressure, a line conductor passing through a wall of said tank and insulated therefrom, an electrode spaced from said line conductor and adapted to form therewith a spark gap filled with said gaseous dielectric, and dielectric means interposed between said electrode and said tank and subjected to said gaseous dielectric for conveying current due to transient energy from said electrode to said tank.
19. In a protective device, in combination, a tank adapted to contain an electrical apparatus and having confined therein a gaseous dielectric under pressure, a line conductor passing through a wall of said tank, and means formed of solid dielectric material interposed between said line conductor and said tank for conveying current due to transient energy in substantially radial paths from said line conductor to said tank and shaped to provide a surface for the passage of said current to an area increasing as the current approaches said tank, said means being subjected to said gaseous dielectric.
- In testimony that I claim the foregoing as my invention I have hereunto signed my name this 27th day of September, 1922.

FRANKLIN S. SMITH.
